UNITED STATES PATENT OFFICE.

EDWARD A. RIX, OF OAKLAND, CALIFORNIA.

FLUID COMPRESSOR.

Application filed June 13, 1927. Serial No. 198,391.

This invention relates to fluid compressor and particularly to fluid compressor of the single acting super-charging type.

The present application consists of improvements upon the structure shown in Patent No. 1,264,562 issued to me April 30, 1918. That patent shows a method of increasing the volume of air or gas delivered by a compressor by providing a differential cylinder and piston and compressing by the differential piston on its downward stroke a volume of air equivalent to about one-third of the main cylinder capacity to about fifteen pounds gauge pressure and delivering as much as possible of this compressed charge through a flash port into the main cylinder at the end of the intake stroke, the result being that the main cylinder is filled at the beginning of the compressing stroke with air or gas at a pressure of about three pounds or more instead of an atmospheric pressure or slightly less, as in ordinary compressors.

Actual experience has shown that a gain of more than the one-third expected from the differential piston is obtained. This is due to the instantaneous closure of the main inlet valve as soon as the flash port opens and the differential piston discharges its contents into the main cylinder.

It is evident that the relative volumes of the main and the differential cylinder, as disclosed in my former patent above referred to, must be a fixed quantity and the capacity of the small reservoir into which the differential piston compresses its contents has, accordingly, been a fixed quantity equal to one-half the contents of the differential cylinder, so as to obtain about fifteen pounds gauge pressure at the end of the stroke. Experience has shown, however, that while at all atmospheric altitudes and temperatures the relative additional volume given by the differential piston is constant that a still greater volume may be given by the following improvements in construction:

1st. By making the differential displacement of the piston somewhat larger in proportion to the main cylinder.

2nd. By making it possible to vary the volume of the reservoir into which the differential piston discharges.

3rd. To flash the contents of the reservoir into the main cylinder through ports formed in the piston instead of through flash ports formed in the main cylinder.

4th. By placing a by-pass pipe and valve between the super-charging reservoir of each cylinder of a duplex compressor with a plain stop valve in the pipe to regulate the amount of by-pass.

These features constitute the improvements and objects of the present application and they will be fully described in detail by referring to the accompanying drawings in which:

Fig. 1 is a central vertical section of one of the cylinders of a duplex fluid compressor.

Fig. 2 is a side elevation of the cylinders of a duplex fluid compressor.

Referring to the drawings in detail and particularly Fig. 2, J indicates an air compressor cylinder, A the head of the cylinder, 1 and 2, inlet and discharge valves respectively, 4 a main piston and L a differential piston formed by the difference in area between the main piston and the trunk L. Reciprocating motion is imparted to the piston in any suitable manner, for instance through a connecting rod 3. The cylinder may be water jacketed, as indicated at 8, and it is in this instance provided with an auxiliary supercharger reservoir F. Communicating with this reservoir is an inlet valve K and a cylinder B. This cylinder is provided with a piston E and a threaded rod which extends through a head secured on the outer end of the cylinder. This rod is provided with a hand wheel C and movement of the piston E to or away from the chamber F is controlled by rotation of the hand wheel C and the threaded rod. The main piston 4 carries a valve H and flash ports G. The piston is also provided with a flange P and with ring grooves and rings of the usual type.

In natural operation air is admitted to the auxiliary super-charging chamber F through the valve K. This body of air is compressed during the downward stroke of the piston and it is by-passed or flashed into the main cylinder chamber J when the ports G register with the auxiliary chamber. Inlet valve 1 will, of course, also admit air during the downward stroke of the piston, but the air admitted is usually slightly less than atmospheric pressure. The air compressed and flashed through the port G is added to the volume admitted through the valve 1 and a pressure of from three to five pounds is obtained at the end of the downward stroke of the piston. This charge is

compressed and discharged through the valve 2 during the upward stroke of the piston and a material increase in the volume of air or gas discharged is obtained, due to the additional air supplied by the differential piston through the auxiliary chamber F. The final discharge through the valve 2 may be increased or decreased, first, by decreasing the capacity of the auxiliary chamber F, for instance by adjusting or moving the piston E inwardly, and the volume may also be decreased by bypassing air from one auxiliary chamber F to another, as illustrated in Fig. 2. In this instance a duplex super-charger compressor is shown, that is—a two-cylinder unit. Each intermediate chamber is provided with a cylinder B and these cylinders are connected by means of a pipe 9 and a valve D. Thus by fully opening the valve D the final discharge from the compressor is reduced to a minimum, as super-charging air will not be added to the cylinders J as the air delivered to the auxiliary chambers F by means of the differential pistons will merely surge back and forth through the pipe 9 and the valve D. On the other hand, if it is desired to increase the discharge from the valve 2, it is merely necessary to partially or fully close the valve D. Partial closing of the valve gradually increases the final discharge from the compressor, while total closing of the valve produces the maximum discharge. In the original patent previously referred to, the differential displacement was made as nearly average to all conditions as possible because it was fixed and not variable. The compressor shown in the present invention is designed to take care of a maximum for all requirements, and if less than the maximum is required, it is accomplished by increasing the volume or capacity of the auxiliary chambers F. It is evident that given a fixed displacement by the differential piston, that the amount of this volume which will be flashed into the main cylinder at the end of the stroke will be determined by the super-charger reservoir and the length of time the flashing port G remains open. The greater the pressure in the auxiliary chamber F, the more air will be flashed into the main cylinder J. Hence, by mechanically increasing or decreasing the volume of the auxiliary chamber F, as by means of the piston E, it is possible to increase or decrease the pressure and hence the volume or amount of air flashed into the main cylinder.

This adjustment may be made by hand, as described, to suit existing conditions of altitude or atmospheric temperature.

The placing of the flash ports G in the piston is also an important feature, as it is evident that a flash port in the cylinder

such as disclosed in my former patent, which is positioned at the end of the intake stroke, will reduce the compressing stroke by the height or width of the flash port. This loss of stroke is obviated in the present instance by placing the flash port and a valve in the piston. This change in the position of the flash port is of further importance, as it does away with the former necessity of riding the piston rings over the flash ports when placed in the cylinder.

When the compressor has been arranged and adjusted by varying the volume in the auxiliary chamber to bring about the greatest efficiency, the adjustable parts may be permanently set for such a condition. By using the by-pass valve D, a greater or less amount of air may be flashed into the main cylinders and if the valve is completely open no air will be flashed into the main cylinders, as the air will merely surge back and forth between the chambers F. Hence complete regulation is obtained and the capacity of the compressor may be changed through a range of approximately twenty-five or thirty-five per cent.

Compressors of the type here illustrated are usually arranged in duplex or two-cylinder units. Each cylinder is water jacketed and as the intermediate chambers F are disposed below the water jackets, it is possible to carry them completely around each cylinder. This is also important as it similarly permits the flash ports to be carried completely around the pistons, thus increasing the areas of the same. While the air for super-charging purposes will in most instances be admitted through valves of the poppet type, such as shown at K, it may also be admitted to the chamber F through ports such as shown at M, N, and O. When the air is admitted through the ports N and O it is taken from the atmospheric exterior of the cylinders, but if the air is taken through the ports M and O, port N may be eliminated, as the air will then be admitted through the crank case. Any one of the arrangements shown is feasible and while other features of the invention are more or less specifically illustrated, I wish it understood that various changes may be resorted to within the scope of the appended claims; similarly, that the materials and finish of the several parts employed may be such as the manufacturer may dictate or varying conditions or uses may demand.

What I claim and desire to secure by Letters Patent is:

1. A fluid compressor comprising in combination a cylinder and a piston in said cylinder dividing the same into a main compression chamber and an auxiliary compression chamber, said piston being operable during the major portion of the extension stroke to compress fluid in the auxiliary

chamber and discharge the same into the main chamber, only at or near the beginning of the compression stroke and means for varying the pressure of the fluid in the auxiliary chamber.

2. A fluid compressor comprising in combination a cylinder and a piston in said cylinder dividing the same into a main compression chamber and an auxiliary compression chamber, said piston being operable during the major portion of the extension stroke to compress fluid in the auxiliary chamber and discharge the same into the main chamber, only at or near the beginning of the compression stroke and means for varying the capacity of the auxiliary chamber.

3. A fluid compressor comprising in combination a cylinder and a piston in said cylinder dividing the same into a main compression chamber and an auxiliary compression chamber, said piston being operable during the major portion of the extension stroke to compress fluid in the auxiliary chamber and discharge the same into the main chamber, only at or near the beginning of the compression stroke and an adjustable displacement member in communication with the auxiliary chamber to vary the capacity thereof.

4. A fluid compressor comprising in combination a cylinder and a piston in said cylinder dividing the same into a main compression chamber and an auxiliary compression chamber, said piston being operable during the major portion of the extension stroke to compress fluid in the auxiliary chamber and discharge the same into the main chamber, only at or near the beginning of the compression stroke, and means whereby a portion or all of the fluid compressed in the auxiliary chamber may be discharged therefrom before discharging the same into the main chamber.

5. A fluid compressor comprising in combination a cylinder and a piston in said cylinder dividing the same into a main compression chamber and an auxiliary compression chamber, said piston being operable during the major portion of the extension stroke to compress fluid in the auxiliary chamber and discharge the same into the main chamber, only at or near the beginning of the compression stroke, a cylinder-like extension in communication with the auxiliary chamber, a piston mounted in said extension and means whereby the position of the piston within said extension may be adjusted to increase or decrease the capacity of the auxiliary chamber.

6. A fluid compressor comprising in combination a cylinder and a piston in said cylinder dividing the same into a main compression chamber and an auxiliary compression

chamber, said piston being operable during the major portion of the extension stroke to compress fluid in the auxiliary chamber, said piston having ports formed therein forming communication between the main compression chamber and the auxiliary chamber only at or near the beginning of the compression stroke and a valve in said piston adapted to open and close said ports.

7. A fluid compressor comprising in combination a cylinder and a piston in said cylinder dividing the same into a main compression chamber and an auxiliary compression chamber, said piston being operable during the major portion of the extension stroke to compress fluid in the auxiliary chamber, said piston having ports formed therein forming communication between the main compression chamber and the auxiliary chamber only at or near the beginning of the compression stroke, a valve in said piston adapted to open and close said ports, and means for admitting fluid to the auxiliary chamber during the compression stroke of the piston.

8. A fluid compressor comprising in combination a cylinder and a piston in said cylinder dividing the same into a main compression chamber and an auxiliary compression chamber, said piston being operable during the major portion of the extension stroke to compress fluid in the auxiliary chamber, said piston having ports formed therein forming communication between the main compression chamber and the auxiliary chamber only at or near the beginning of the compression stroke, a valve in said piston adapted to open and close said ports, means for admitting fluid to the auxiliary chamber during the compression stroke of the piston, a cylinder in communication with the auxiliary chamber and an adjustable piston in said cylinder to regulate the amount of air admitted to the auxiliary chamber and the cylinder during the compression stroke of the piston.

9. In a fluid compressor of the character described a pair of cylinders, a piston in each cylinder, said pistons dividing each cylinder into a main and an auxiliary compression chamber, said pistons being operable during their extension strokes to compress fluid in the auxiliary chambers and discharge the same into the main chambers at or near the beginning of the compression stroke, and means whereby a portion or all of the fluid compressed in the auxiliary chambers may be by-passed back and forth between the auxiliary chambers in the respective cylinders.

10. In a fluid compressor of the character described a pair of cylinders, a piston in each cylinder, said pistons dividing each cylinder into a main and an auxiliary com-

pression chamber, said pistons being operable during their extension strokes to compress fluid in the auxiliary chambers and discharge the same into the main chambers at or near the beginning of the compression stroke, a pipe connecting the auxiliary chambers and an adjustable valve in said

pipe whereby a portion or all of the fluid compressed in the auxiliary chambers may be by-passed back and forth between the auxiliary chambers in the respective cylinders.
